ORNAMENTAL BAND FOR WASHING
MACHINE TUBSElmer C. Cooley, Syracuse, N. Y., assignor to Easy
Washing Machine Corporation, Syracuse, N. Y.,
a corporation of Delaware

Application June 9, 1939, Serial No. 278,202

3 Claims. (Cl. 41—34)

This invention relates to improvements in washing machines or the like in which metal bands or straps are provided for ornamental purposes.

5 An object of this invention is to provide an ornamental band of the type described which is of such construction and so protected and reinforced by the adjacent surfaces of the article to which it is applied, that light, flexible sheet 10 metal may be used for the band without sacrificing strength and while giving an appearance of great solidity to the band.

15 A further object of this invention is to provide a washing machine tub or the like with an ornamental band or strap which may be quickly and easily secured to the tub in cooperative relation therewith without the use of screws, bolts or the like or tools for manipulating the same.

20 Another object of the invention is to provide an ornamental band or strap for a clothes washing machine tub with means engaging the ends of the band or strap adapted to resiliently urge relative movement of the ends with respect to each other whereby the band or strap will be 25 maintained in tight gripping engagement with the tub irrespective of variations within limits in the length of the strap or band or in the circumference of the tub, whether due to expansion or contraction or to any other cause.

30 I attain these objects by the construction illustrated in the accompanying drawing, in which:

Figure 1 is a perspective view of a clothes washing machine having ornamental bands constructed in accordance with this invention associated therewith.

35 Figure 2 is an enlarged detail vertical sectional view through one of the ornamental bands and the adjacent portion of the washing machine tub taken substantially in the plane of the line 40 2—2, Figure 1.

Figure 3 is an enlarged detail horizontal sectional view taken substantially in the plane of the line 3—3, Figure 1, illustrating the ends of the band positioned in cooperative relation with each other within the usual shroud for the wringer drive shaft housing of the washing machine.

45 Figure 4 is a detail side elevation as viewed from line 4—4, Figure 3, illustrating the adjacent ends of the band or strap with my novel spring clamp connected therewith for securing the band or strap to the tub of the washing machine.

50 Figure 5 is an exploded perspective view illustrating the adjacent ends of the band or strap

and the spring clamp constructed in accordance with this invention.

The washing machine, as illustrated in Figure 1 of the drawing, comprises the usual tub or vat 10 and a skirt or apron 11 arranged beneath the vat 10 for concealing the drive mechanism (not shown) of the washing machine which is usually mounted beneath the tub 10. The washing machine is also illustrated as being provided with a shaft 12 extending upwardly from the lower portion of the apron 11 exteriorly of the tub or vat 10 for driving the rolls of a wringer 13. The shaft 12, as illustrated in Figure 3, is mounted in a tubular case or housing 14 which is concealed within a suitable shroud 15, primarily for the sake of appearance.

The washing machine is illustrated in Figure 1 as being provided with three of my novel ornamental bands or straps 17 arranged in substantially parallel vertical spaced relation to each other, one band being mounted at the junction of the skirt 11 and vat 10 for concealing the joint formed thereby and the other two bands being arranged on the tub 10 in close relation to the lower band 17.

25 Each ornamental band 17 is composed of a narrow strip of thin sheet metal having a length substantially equal to the circumference of the tub 10 so as to encircle said tub. These bands are usually chromium plated or otherwise treated, 30 as with paint or enamel, so that the outer surface thereof pleasingly contrasts with the outer peripheral surfaces of the tub 10 and apron 11.

35 The washing machine is preferably provided with a series of parallel grooves or recesses in the outer peripheral surface thereof, one for each band 17. The grooves 18 for the two upper bands 17 are formed in the tub 10 as illustrated in Figure 2, while the groove or recess for the lowermost band 17 may be substantially similar except that it is formed by the adjacent edges of the vat 10 and the apron 11. The groove 18 shown in Figure 2 has an arcuate central portion 19 of substantially the same width as the width of a band 17. The central portion 19 has 40 its intermediate portion terminating inwardly from the normal plane of the outer peripheral surface of the tub a distance substantially equal to the thickness of the band 17 while its upper and lower side portions 19' terminate inwardly 45 a short distance from the normal plane of the outer face of the tub. The side portions 19' are connected with the adjacent portions of the vat 10 by the reversely curved portions 20 which provide annular channels 20' adapted to receive the 50 55

longitudinal side portions 21 of the band 17 therein.

The band 17 is slightly curved transversely so as to conform closely to the contour of the arcuate central portion 18 of the groove 18, as indicated in Figure 2, so that when the band is clamped around the tub said band will be snugly maintained in substantially fixed predetermined relation with the tub. By this construction, I 10 am enabled to use thin sheet metal for the bands 17 without rendering them unduly liable to be dented or marred in service, as each band is reinforced throughout its entire width and length by the arcuate portion 18 of the groove 18. Furthermore, the edges 21 of the band are protected 15 by being seated in the annular channels 20', and this not only prevents the edges of the band from being accidentally caught and raised or bent, but the arcuate construction gives the band 20 a desirable appearance of solidity and strength.

As hereinbefore stated, the band of strap 17 is of such a length with respect to the circumference of the tub 10 and more particularly to the circumference of the groove 18 that, when 25 mounted in said groove, the ends 22 of the band or strap will terminate adjacent each other, as indicated in Figures 3 and 4. In order that the ends 22 of the band 17 may be concealed, it is preferable that the band be so mounted on the tub that said ends will be positioned within the shroud 15 for the wringer drive shaft housing 14. However, it will be understood that the band may be so mounted that its ends 22 may be concealed beneath other members associated with the tub 30 depending upon the structure of the washing machine. The ends 22 of the band are formed substantially flat and in substantially right angular relation to the plane of the remaining portion of the band. This is accomplished by bending the central portion of the band outwardly, as at 23, Figure 3, a distance substantially equal to one-half the normal width of the band 17 and also bending the adjacent side portions inwardly 40 toward each other so that said side portions lie in superposed relation substantially midway of the band with the inner edges thereof in substantially the plane of the inner surface of the body portion of the band, as indicated in Figure 45. 3. Each flat end portion 22 of the band is provided with a hole 24 stamped or otherwise formed 50 therein.

The ends 22 of the band, in this instance, are tied to each other by my novel resilient clamp 25 which is composed of a single piece of spring wire of slightly less diameter than that of the holes 24 so as to readily extend through said holes. The clamp is formed by bending the wire in such a manner as to provide a loop 26 and two jaws 27 at one side of the loop. Each jaw 60 27 is provided with a bend or niche 28 in its inner face. These bends 28 are adapted, when the jaws are in engagement with the ends 22 of the band, to prevent the clamp and band ends from moving out of engagement with each other. The 65 bends 28 of the jaws 27 are normally yieldingly

maintained by the loop 26 in spaced relation to each other a distance slightly less than the distance between the holes 24 when the band 17 is mounted in a recess 18.

When positioning the band 17 on the tub, the 5 band is wrapped about said tub in engagement with the arcuate surface 18, after which the ends or jaws 27 of the clamp 25 are inserted into the holes 24. Inasmuch as the bends 28 of the jaws 27 are normally spaced apart a distance less than 10 the normal distance between the holes 24 when the band is mounted in a recess 18, the clamp 25 will be under spring tension when in engagement with the ends 22 and yieldingly urges said ends toward each other and thereby cooperates 15 with the curved portion 18 of the groove 18 in maintaining the band in fixed predetermined relation with the tub 18.

Although the construction and application of my band and clamp are particularly simple, practical and efficient, it is evident that various changes may be made in the details thereof without departing from the spirit of the invention as set forth in the appended claims.

I claim:

1. An ornamental band of the class described comprising a narrow strip of flexible metal, said strip having flat end portions extending longitudinally of the strip and disposed at right angles to the main portion thereof, said end portions having holes therein, and a loop spring clamp provided with jaw members extending into said holes for maintaining said end portions in close relation to each other and urging said band into engagement with an object confined thereby, the loop of said clamp being arranged at one side of said flat end portions with the axis thereof extending substantially normal to the plane of said end portions whereby said clamp is positioned in close proximity to the object confined by the band.

2. An ornamental band of the class described composed of a narrow strip of flexible metal initially of substantially equal width throughout its length, said strip having portions at opposite sides of its center line adjacent each end thereof bent into overlying relation with each other to provide substantially flat end portions extending longitudinally of the strip at right angles to the main portion of said strip, said end portions having holes therein, and a spring clamp formed of a single piece of wire having its intermediate portion bent into a loop and its ends extending outwardly from one side of the loop in substantially the plane thereof and into said holes for maintaining said end portions in close relation with each other and urging said band into engagement with an object confined thereby.

3. An ornamental band structure as defined in claim 2 wherein said ends of the clamp have portions bent laterally to form niches at the inner sides thereof registering with the corresponding flat end portion for removably securing the clamp and band to each other.

ELMER C. COOLEY. 6.
